UNITED STATES PATENT OFFICE.

JAMES A. GRAHAM, OF FORT WAYNE, INDIANA.

DRAFT-RIGGING FOR RAILWAY-CARS.

SPECIFICATION forming part of Letters Patent No. 402,581, dated May 7, 1889.

Application filed September 8, 1888. Serial No. 284,872. (No model.)

To all whom it may concern:

Be it known that I, JAMES A. GRAHAM, of Fort Wayne, Allen county, State of Indiana, have invented a new and useful Improvement in Draft-Rigging for Railway-Cars, of which the following is a true and exact description, reference being had to the accompanying drawings, which form a part of this specification.

10 My invention relates to the construction of the draft-rigging of railway-cars, and has for its object to so construct the draft-rigging and combine it with the car-body as to make a rigging at the same time cheap, rigid, durable, and easily adjusted for any length of draw-bar.

Reference being now had to the drawings which illustrate my invention, Figure 1 is a central longitudinal sectional elevation of my 20 draft-rigging applied to a railway-car; Fig. 2, an end view on the section-line $x x$ of Fig. 1; Fig. 3, a view on the section-line $y y$ of Fig. 1. Fig. 4 is a plan view of one of the draft-irons shown in elevation in Fig. 1. Figs. 5 25 and 6 are respectively a side elevation and a plan view of one of the two buffer blocks or castings, and Figs. 7 and 8 are respectively a plan view and an elevation of one of the key-blocks used in uniting the draft-timbers 30 with the center stringers.

A indicates the flooring of a railway-car; B, its end sill; C C, the center stringers; D, the body-bolster; D', the king-bolt and castings whereby the body-bolster is united to a truck.

35 E is the coupling or draw-bar, e being a shoulder resting against one follower, and e' a key resting against a washer on the opposite follower.

F is the draw-bar stirrup; f f and h' h', 40 bolts uniting it to the end sill and draft-timbers.

G G are bearing-rod; H, a solid block of timber framed in between the center stringers, and extending from the end sill, B, to a 45 point preferably back of the body-bolster D. Heavy bolts h h, &c., are used to secure the block H to the center stringers.

h' and h² are shoulders cut in the block H to secure the thrust of the buffer-castings.

50 I is a chafing-iron; J J, the draft-timbers, which are firmly secured to the center stringers and end sill by bolts l l, L, l l, o, and L',

the abutting faces of the timbers being cut away around bolt L, as shown at k, to admit the key-block K.

55

O O, &c., are cross-straps extending from one draft-timber to the other, and secured in place by the bolts which unite them to the stringers.

N N are draft-irons secured along the bottom of timbers J J, as shown.

n n are turned-up ends of the draft-iron, by which their hold on the timbers is made secure; n' n', recesses cut in the draft-irons to admit the bottom edges of the buffer-blocks, 65 and n² n², &c., bolt-holes through which the bolts l l, &c., pass.

P P are the buffer-blocks, alike in all respects, P' being an upwardly-extending shoulder, P² its bottom edge, and P³ the opening 70 through which the follower passes. The buffer-blocks are wider than the distance between the draft-timbers, which have grooves cut in them to receive the edges of the blocks.

R R are the followers; S, the openings between the followers; m m, &c., bolts passing through the buffer-castings and the draft-timbers to secure them together, as shown, washer-plates M M being secured on the outside of the timbers.

80

The draft-rigging is put together by inserting the buffer-castings between the draft-timbers, so that their upwardly-extending shoulders will rest respectively against the shoulders h' and h², formed in block H. (The position of these shoulders of the slots in the draft-timbers and of the draft-irons or of the slots n' cut in them may be varied at will to suit different draw-bars. The shoulder h', for instance, may be against the end sill, B.) The 85 edges of the buffer-castings rest in slots formed in the draft-timbers, and at their lower ends enter and rest against the slots n' of draft-iron N. The bolts m are inserted and bind the draft-timbers and buffers together in a most secure and rigid manner. The followers and springs are then inserted and the draw-bar pin is passed through them and keyed, as shown.

The great strength and rigidity of the construction described will be at once perceived. By the device of using the upwardly-extending shoulder of the buffer-castings in connection with the block H buffering-shocks are to 100

a great degree removed from the draft-timbers and distributed through the car, and even apart from this feature my construction is so strong and simple as to be exceedingly useful.

Having now described my invention, what I claim as new, and desire to secure by Letters Patent, is—

1. In a draft-rigging, the combination, with the center stringers, of a railway-car with a block, H, framed between and bolted securely to said stringers, draft-timbers J J, cross-straps O, and draft-irons N N, bolted firmly together and to the center stringers, and buffer-blocks secured between the draft-timbers and bolted thereto.
2. In a draft-rigging, the combination, with the center stringers, of a railway-car with a block, H, framed between and bolted securely to said stringers, draft-timbers J J, cross-straps O, and draft-irons N N, having slots n' n' bolted firmly together and to the center stringers, and buffer-blocks having their lower edges formed to enter slots n' of the draft-irons secured between the draft-timbers and bolted thereto.
- 25 3. In a draft-rigging, the combination, with

the center stringers, of a railway-car with a block, H, framed between and bolted securely to said stringers, draft-timbers J J, cross-straps O, and draft-irons N N, bolted firmly together and to the center stringers, and buffer-blocks P, having upwardly-extending shoulders P', formed to extend above and rest against shoulders h' h², formed in block H, 30 said blocks being secured between the draft-timbers and bolted thereto.

4. In a draft-rigging, the combination, with the center stringers, of a railway-car with a block, H, framed between and bolted securely to said stringers, draft-timbers J J, cross-straps O, and draft-irons N N, having slots n' n' bolted firmly together and to the center stringers, and buffer-blocks P, having their lower edges, P², formed to enter the slots 40 n' of the draft-irons, shoulders P', formed to extend above and rest against shoulders h' h², formed in block H, said blocks being secured between the draft-timbers and bolted thereto.

JAMES A. GRAHAM.
